CONTAINER FOR CUBE-SUGAR WITH DELIVERY DEVICES

Application filed May 27, 1930, Serial No. 456,271, and in Germany May 29, 1929.

The present invention relates to a container for cube-sugar combined with a device for the delivery of single pieces of sugar, in which the pieces of sugar are accommodated without order, so that they need not be touched or fingered in the operation of filling the container. This is particularly valuable and desirable for hygienic reasons.

The chief novel features of the sugar container constructed according to the present invention reside in the provision, at the bottom thereof, of a downcomer that is a vertical tube having a delivery opening and an ejecting flap, while another tube is telescopically mounted on the downcomer so as to be capable of sliding thereon. The latter tube is likewise provided with a delivery opening and adapted to control the said ejecting flap.

Various other features and advantages will become apparent during the continuance of the following description.

In the accompanying drawings forming a part of this specification and showing for purposes of exemplification a preferred form and manner in which the invention may be embodied and practised:

Figure 1 is a somewhat diagrammatic view in elevation partly in section of the improved sugar container in closed condition;

Figure 2 is a similar view of the container in delivery condition;

Figure 3 is a view in top plan thereof; and

Figures 4 to 6 illustrate certain details.

As will be seen in the drawings the sugar container according to the present invention comprises in a vessel for the reception of the cube-sugar including a funnel-shaped bottom *b*, and the base portion including the delivery device which essentially is composed of the two telescopically slidible tubes.

The one or outer tube *c* projects upwards through the bottom *b* and three radial arms *a* are symmetrically mounted on the top end of the tube and adapted to move up and down together with the tube *c* when the latter is telescopically displaced on the inner stationary tube or downcomer *d*. The latter is provided with a lateral handle *g* and is normally kept in elevated position by a coiled spring

l abutting against an annular flange *k* of the tube *c* as will be seen in Figure 1.

The tube *c* is laterally recessed to form a delivery opening *i* and the downcomer *d* is also recessed to form a delivery opening *y* the two openings *i* and *y* registering when the parts occupy the delivery positions as will be seen in Figure 2.

Diametrically opposite the opening *i* of the tube *c*, there is provided a second recess *h* and similarly in the downcomer *d* there are provided recesses *e* and *f*. The recesses *h*, *e*, *f* receive the ejecting flap *o* pivotally mounted on a horizontal shaft *q* supported in suitable bearings provided in the base portion of the container. Mounted on the shaft *q* so as to be capable of swinging thereabout, is a lever *r* equipped with an arm or feeder *n* and controlled by a draw-spring *m*.

The lower edge *x* of the ejecting recess or opening *i* of the tube *c* serves to normally support the flap *o* while the lower edge *s* of the opposite recess or opening *h* of the tube *c* releases the lever *r* and consequently the arm or vane *n* when or as the ejecting tube *c* reoccupies its uppermost position.

The handling or operation of the device is as follows:

The pieces of sugar are discharged from the device singly and in succession as desired. When a piece is wanted to be delivered, the tube *c* is to be moved downwards by means of the handle *g* see Figure 2 whereby the ejecting flap *o* is caused to turn or swing downwards under the weight or load of the piece of sugar supported by the flap. It will be seen in Figure 2 that pieces of sugar are piled up in the downcomer singly, that is one on top of the next preceding one, and that therefore only a single piece can be discharged at a time. Thus only the lowermost piece of sugar will be delivered from the tilted flap. For as the tube *c* is shifted downwards manually by means of the handle *g* the lever *r* will be released and allowed to swing about the axis or shaft *q* due to the action of the draw-spring *m* so as to cause the arm or feeder *n* rigidly connected with the said lever, to come in contact with the next following piece of sugar and to arrest the lat-

ter by forcing the same towards and in contact with the inner surface of the wall of the downcomer *d* whereby not only the next following piece of sugar but also the whole 5 pile of sugar pieces in the downcomer will be retained in position as will be readily understood upon inspection of Figure 2.

Subsequently when the handle *g* is released the spring *l* will act to move the tube 10 *c* upwards and to enter the vessel by projecting through an opening in the bottom *b* thereof, the arms or vanes *a* acting to loosen the charge of sugar pieces in the vessel and to thereby prevent the same from obstructing 15 the mouth of the downcomer and from being jammed therein.

From the foregoing it will be seen that single and efficient means are herein provided for accomplishing the objects of the invention, but while the elements shown and described are well adapted to serve the purposes for while they are intended its to be understood, that the invention is not limited to the precise construction set forth, but includes within its purview such changes as 25 may be made within the scope of the appended claims.

What we claim is:

1. A container for cube-sugar with a delivery device, comprising in a vessel with a bottom and a base-portion below the bottom a downcomer below the said bottom, a delivery recess in the downcomer, an ejecting flap in the said downcomer, a telescopically 30 displaceable tube on the downcomer adapted to project into the said vessel and to operate the said flap and a delivery recess or opening in the said tube.

2. A container for cube-sugar with a delivery device, comprising a vessel with a bottom and a base-part below the bottom, a downcomer below the said bottom a delivery recess or opening in the slide wall of the downcomer, an ejecting flap in the said 45 downcomer a telescopically displaceable tube on the downcomer adapted to project into the said vessel and to control the said flap a delivery recess or opening in the said wall of the said tube, a plurality of horizontal arms 50 or vanes at the top of the tube, and an opening in the bottom for the tube and vanes to project therethrough, substantially as and for the purpose set forth.

3. A cube-sugar container as claimed in 55 claim 2 wherein the ejecting flap is pivotally supported in recesses of the downcomer and the tube surrounding the latter, the tube being adapted to normally hold the flap in position for closing the delivery recess or opening of the downcomer.

4. A cube-sugar container as claimed in 60 claim 2, wherein an arm or feeler is pivotally connected with the flap so as to move simultaneously with the flap, when the latter is opened, and to move individually and act at

the same time to arrest and withhold the several sugar pieces in the downcomer except the lowermost one, a draw-spring being provided for moving the said arm or feeler individually.

5. A cube-sugar container as claimed in 70 claim 2, wherein the lower edge of the ejecting recess or opening of the tube serves to support the flap, while the lower edge of the opposite recess or opening of the tube acts to release a lever forming a part of the flap and carrying the arm or feeler, when the 75 ejecting tube reoccupies its uppermost position.

6. A cube-sugar container as claimed in 80 claim 2, wherein the arms or vanes are arranged in a manner, that when the ejecting tube is moved to its lowermost position, the upper edges of the said arms or vanes will lie approximately in the plane of the bottom of 85 the vessel.

In testimony whereof we affix our signatures.

ADOLF RACUSIN,
JOSEF SPIRA.
